UNITED STATES PATENT OFFICE.

REBECCA HARRIS, OF NEWARK, NEW JERSEY.

ARMY AND NAVY PILLOW KIT.

1,269,276.

Specification of Letters Patent. Patented June 11, 1918.

Application filed November 10, 1917. Serial No. 201,283.

To all whom it may concern:

Be it known that I, REBECCA HARRIS, a citizen of the United States of America, residing at Newark, in the county of Essex 5 and State of New Jersey, have invented certain new and useful Improvements in Army and Navy Pillow Kits, of which the following is a specification.

This invention relates to certain new and 10 useful improvements in army and navy pillow kit.

The primary object of the invention is the provision of a compact kit for the use of soldiers whereby a large number of small 15 articles such as soap, brush and comb and a razor may be easily carried while the device is serviceable as a pillow covering when desired, the same being of simple construction, easy and inexpensive to manufacture.

20 A further object of the device is the provision of a pillow formation, adaptable for a plurality of uses such as a carrying kit, muffler, helmet, knapsack, laundry bag and game-board, provision being made for rendering the same waterproof when employed 25 for use.

A still further object of the device is to provide a serviceable covering adapted for arrangement in pillow formation without 30 the necessity of stitches and whereby the device may be employed in its unfolded arrangement or as a body protector when desired and then arranged for immediate use as a pillow covering for stuffing with any 35 available articles when desired for use as a pillow.

With these general objects in view and others that will appear as the nature of the invention is better understood, the same consists in the novel construction, combination 40 and arrangement of parts hereinafter more fully described, illustrated in the accompanying drawing and then claimed.

In the drawing forming a part of this 45 application, and in which like reference characters refer to corresponding parts throughout the several views,

Figure 1 is an elevational view of the device, arranged as a pillow,

50 Fig. 2 is a developed plan view of the interior of the device entirely unfolded and

Fig. 3 is a perspective view of the inner side of one of the lateral edges thereof.

It being understood that the device is 55 serviceable for many different uses, and may be made in any desired sizes, the same

broadly consists in a rectangular body portion 10 formed of any flexible material such as leather or fabric, and preferably having one or both surfaces thereof suitably waterproofed. The opposite edges 11 of the body 10 are arranged with separable fasteners 12 of any suitable form, whereby the said edges 11 of the body 10 are adapted to be detachably connected in overlapped relations. 60

This connection between the edges 11 arranges the body 10 in tubular form and it may then be partially filled with any suitable material, such as straw or feathers for forming a pillow or cushion, it being noted 70 that gathering strings 13 are shirred through hems 14 arranged in the body 10 in spaced relation to the lateral edges 15 and 16 thereof. It will be evident that when stuffing material is positioned within the tubular body 10, the strings 13 may be tightened and their opposite ends tied together, arranging the device as a pillow as best 75 illustrated in Fig. 1 of the drawing.

The lateral portion or flap 17 of the body 80 10 which is arranged adjacent one of the gathering strings 13 and body edge 15 is provided with separable fasteners 18 whereby the said portion 17, which is of the form of an oblong rectangle will form an inclosing end portion or compartment 19. Any desired articles such as handkerchiefs may be positioned within the end compartment 19 ready for instant use by disengaging the 85 fasteners 18 of the said end. 90

The opposite laterally positioned portion 20 which is of rectangular form and positioned between the other draw-string 13 and the body edge 16 is adapted for a similar purpose but is arranged with separate 95 pockets 21, opening inwardly of the body 10 while separable fasteners 22 are arranged for closing the pocketed end 23 when the device is arranged as a pillow. A game-board 24 is arranged upon the inner face of the 100 body 10, preferably centrally thereof adapted for use in playing such games as checkers or chess when the body 10 is in its flat open position when not desired as a pillow-cover. 105

Additional pockets 25 may be arranged upon the marginal portions of the body 10 adjacent the game-board 24 for holding any desired articles, while of course, any of the said pockets may be omitted if desired. 110

The device may be arranged as shown in Fig. 1 and upon releasing the side fasten-

- ers 12, the filling material can be removed and the folded body 10 then worn as a muffler, belt, or similar article of wearing apparel, the same possessing considerable warmth. The pillow may be filled with articles such as a camp outfit or eatables and used as a knapsack, while it may also be used as a helmet or a laundry bag if occasion requires.
- 10 It will be understood that buttons or any other suitable connectors may be arranged for the edges of the device body 10 and that other details of construction may be altered and changed at will without departing from the spirit and scope of the invention as hereinafter claimed.

A serviceable camp article which gives added comfort to the soldier is provided while the device is easy and inexpensive to manufacture and may be formed of such material as to render the same extremely strong and serviceable.

What I claim as new is:—

1. A device of the class described comprising a rectangular body adapted for assuming tubular formation, separable fasteners arranged around the edge of the body, draw-strings arranged through the body spaced from its opposite ends adapted for separating a central pillow portion with

closable end compartments, the latter being adapted for the reception of articles.

2. A soldier's kit bag comprising a body of flexible material adapted for tubular arrangement, coöperating separable fasteners at the edges of the body whereby the latter may assume its tubular form with the ends of the bag adapted for closing at will, and gathering-strings carried by the body in spaced relations from each other and from the ends of the body, adapted for forming a central pillow portion and opposite end compartments when the body is in its tubular arrangement.

3. A bag comprising a rectangular body of flexible material adapted for tubular arrangement, securing means at the edges of the body whereby the latter may assume its flat arrangement or tubular form at will, gathering-strings carried by the body in spaced relations from each other and from the ends of the body, adapted for forming a central pillow portion and opposite end compartments when the body is in its tubular arrangement, the said securing means being also adapted for closing the said end compartments, and a plurality of pockets arranged within one of the end compartments.

In testimony whereof I affix my signature.
REBECCA HARRIS.
